STAMP MILL

Benjamin B. Buck, Los Angeles, Calif.

Application August 12, 1936, Serial No. 95,587

20 Claims. (Cl. 83—57)

This invention relates to a machine for reciprocating a plunger, and the invention is useful in any situation where the reciprocating plunger operates to give an impulse to any part, or deliver a blow, for example, upon a die or anvil.

The invention is particularly useful when applied to the construction of stamp mills such as used in mining districts for milling ore.

The general object of this invention is to provide a machine for reciprocating a plunger, and particularly adaptable for use in the construction of a stamp mill, which will overcome many of the objections and drawbacks of mills constructed in accordance with the present practice.

One of the objects of the invention is to provide a machine of simple construction, in which the impetus is given to the plunger, or stamp, by means other than gravity. In this way, with a comparatively short stroke the plunger can be given a relatively high velocity, giving a greatly increased energy of impact as compared with plungers that merely descend by gravity.

In its general construction the invention involves the use of a power cylinder carrying a piston, which is driven forward by power, and which operates to drive forward the plunger.

One of the objects of the invention is to provide a construction and mode of operation for a machine of this type, which will enable a separation to be effected between the power piston and the plunger before the plunger strikes the blow. In this way shocks to the power piston and its gas rings are avoided, and the life of the mill is greatly enhanced.

Amalgamating processes are still used in reducing and refining precious metals, but it is objectionable to have oil mixed with the milled ore, as the presence of such oil interferes with the amalgamating process.

One of the objects of this invention is to provide a construction for the mill, which will effectively prevent any oil from passing into the milled ore.

A further object of this invention is to provide a machine of very compact construction, capable of reciprocating a plunger at a high velocity, but without employing a rotary shaft; also to provide a machine of this kind particularly adapted for use as a stamp mill, and having a relatively high stamping capacity as compared with the weight of the machine.

A further object is to construct the machine in such a way that its separate parts will be sufficiently light to enable them to be readily trans-

ported in a difficult country where it may be necessary to set up a stamp mill.

A further object of the invention is to provide a mill of this type with special means for facilitating the cooling of the power piston.

A further object of the invention is to provide a construction and mounting for a mill of this type, which will enable the stroke of the mill to be adapted to the special requirements of the material that is being milled; in other words, to provide a construction which will enable the shoe to have a relatively short travel before it strikes the die, or a relatively long travel.

A further object of the invention is to provide fluid-operated means for returning the plunger and the power piston after a forward stroke.

A further object of the invention is to provide the necessary valves, ignition means, etc., for operating a machine of this type, and to provide means for controlling the same automatically by the return stroke of the plunger.

Although I do not limit myself to the use of a combustible fuel for operating the power cylinder, in the present specification, I have described the use of a combustible fuel for this purpose; and one of the objects of the invention is to provide a construction for the machine, which will operate to maintain a supply of heated air to the fuel feeding apparatus.

In operating a mill that strikes a blow on an anvil, a considerable shock occurs to the mechanism of the mill when the plunger and shoe carried thereby strikes the anvil or die. One of the objects of this invention is to provide means associated with the shoe for absorbing a portion of the shock which occurs when the blow is struck.

The machine embodying my invention preferably employs compressed air for returning the plunger and the power piston after their forward stroke. One of the objects of the invention is to provide a machine of this kind with means enabling it to compress air during its own operation, in a quantity more than sufficient to operate the machine. Hence it is only necessary to employ a small quantity of compressed air in starting up the machine.

Further objects of the invention will appear hereinafter.

The invention consists in the novel parts and combination of parts to be described herein-after, all of which contribute to produce an efficient stamp mill.

A preferred embodiment of the invention is described in the following specification, while the

broad scope of the invention is pointed out in the appended claims.

In the drawings:

Figure 1 is a vertical section through a machine embodying my invention, and designed particularly to function as a stamp mill.

Figure 2 is a horizontal cross-section taken on the line 2—2 of Figure 1, and particularly illustrating the construction at the lower end of the return cylinder that functions to return the plunger and power piston after a forward stroke.

Figure 3 is a view upon an enlarged scale similar to Figure 1, but showing only substantially the upper half of Figure 1.

Figure 4 is a view upon an enlarged scale similar to Figure 1, but showing only the lower half of Figure 1.

The dot and dash line M—M at the top of Figure 3 and the bottom of Figure 4 is a matching line drawn through identical positions of the two figures.

Figure 5 is a fragmentary vertical section upon an enlarged scale, and illustrates the detail of an air inlet for cooling the power piston.

Figure 6 is a fragmentary vertical section taken on the line 6—6 of Figure 2 upon an enlarged scale, and further illustrating the details at the lower end of the return cylinder.

Before proceeding to a more detailed description of the invention, it should be stated that in accordance with the invention, I provide a power cylinder in which a power piston reciprocates. After the forward stroke, the power piston is returned automatically to its initial position. In commercial use any suitable means may be employed to utilize the power developed by the power piston in its forward stroke. When the invention is employed in the construction of a machine for delivering blows, for example, a stamp mill, I prefer to construct the power piston so that it is a separate part from the plunger, but abuts against the plunger so that when the power piston is advanced by the driving force, it also advances the plunger. In order to avoid giving a shock to the power piston when the plunger delivers a blow, in the preferred form of my invention the power piston is unattached to the plunger. The plunger is automatically returned, and while the returning plunger could be utilized to return the power piston to its initial position, in the present specification I have described the power piston as being provided with its own returning means.

The machine is characterized by the use of a floating plunger, preferably unattached to the driving power piston and not connected with any rotary shaft, and while, for a power developing mechanism this plunger could be made to operate in a horizontal direction, of course, in adapting the invention for use in the construction of stamp mills, the machine is of a vertical type, that is to say, the plunger reciprocates in a substantially vertical plane.

In the operation of the machine, on the forward stroke, means is provided for retarding the forward movement of the power piston so that when the plunger strikes a blow, it is not in contact with the power piston.

The power piston is preferably provided with its own return piston reciprocating in the return cylinder, and operating fluid admitted to the return cylinder forces the power piston back to its initial position. However, the air or other operating fluid in the return cylinder in advance of the return piston of the power piston, does

not interfere with the forward advance of the power piston, due to the fact that relief valves are provided, which open automatically to permit the escape of the air before the advancing power piston, which otherwise would become highly compressed, and interfere with the development of the full force of the blow. The air forced out of the return cylinder on the down stroke of the plunger passes up to the fuel injection apparatus, thereby reducing the air volume and air pressure resistance to the striking stroke of the plunger.

The other end of the return cylinder is utilized as a compressor for compressing air, which is forced into an air reservoir, which contains a supply of compressed air for the operation of the machine. In the operation of the machine, after a blow is struck, an ample supply of operating fluid, or air, is admitted to the lower end of the return cylinder to effect the return of the power piston and plunger to their initial position; in other words, to insure the lifting of the stamp shoe to the height of its travel above the die, or anvil. The shoe of the plunger head is preferably provided with an outer sleeve, or apron, which prevents any possibility of lubricating oil passing down into the ore being milled, and during the upstroke, this outer sleeve or apron functions to control the moving parts, such as valves, and ignition means for the machine.

When the shoe has delivered a blow to the ore on the die, if the amount of material on the die is so reduced that the shoe approaches within a predetermined limit of the face of the die, then automatic means, preferably pneumatic means, is controlled to feed more ore onto the die.

The position of the reciprocating floating plunger with respect to the die, can be regulated to suit different materials being milled; in other words, if the ore is relatively difficult to mill, the stroke of the plunger before it strikes the anvil, can be readily increased, and vice versa.

The invention as applied to a vertical type of machine, will now be described more in detail.

At the outer or upper end of the machine I provide a power cylinder 1, in which power is developed to advance a power piston 2 that drives forward a plunger 3. The cylinder 1 has an elongated cylindrical shell 4, and may be provided with a water jacket 5 for cooling the same. The power piston 2 is unattached to the plunger 3, and when it is driven forward by the operating fluid, it drives the plunger 3 forward, enabling the plunger to give impetus to any driven part or, as in the present instance, to drive a milling shoe, or a head 6 at the forward end of the plunger so that the same can cooperate with a die, or anvil 7 to reduce ore, or other material on the face of the die.

I provide means for returning the plunger after a forward stroke and, of course, the return of the plunger would effect the return of the power piston. However, I prefer to provide a return piston 8 for the power piston which is preferably carried or formed at the lower end of a long sleeve 9, which is rigidly attached to the power piston and extends down from the same within the shell 4 of the power cylinder. This return piston 8 reciprocates in a return cylinder 10, the upper end of which supports the power cylinder 1.

In order to provide for returning the plunger

3 after its forward stroke, I prefer to construct the plunger 3 with a long stem, or mandrel 11, the upper end of which is provided with a return piston 12 that reciprocates within the sleeve 9 of the power piston. After a forward stroke of the power piston and plunger, operating fluid, preferably compressed air, is supplied to the interior of the return cylinder 10 in sufficient quantities to overcome the weight of the plunger and power piston 2, and return same to the elevated position in which they are illustrated in Fig. 1. In the present instance, as the plunger and return piston 8 advances, the air in the interior of the return cylinder 10 and the interior of the sleeve 9, is forced out through outlet valves 13 that are mounted in an air head 14 at the lower end of the return cylinder 10. These valves 13 are preferably of a poppet type opening downwardly, and have return springs 15 of helical form. When they open they admit the air to a valve chest 16 within the air head 14, and this valve chest communicates through arcuate ports 17 with an air jacket space 18 surrounding the return cylinder 10. The air passes upwardly in this jacket space, and passes out of the jacket space through a pipe connection 19 at the left side of the cylinder that carries the expelled air back toward the air reservoir, not illustrated, but which is connected with this pipe 19. These valves 13 therefore permit the escape of the air in the return cylinder 10, and prevent its being compressed to such a high pressure as might give too great a resistance to the forward movement of the plunger and power piston.

35 The machine is preferably constructed so that when the head or shoe 6 strikes the ore on the anvil, or die 7, the power piston 2 will be out of contact with the plunger 3. In order to accomplish this, I prefer to provide an auxiliary 40 exhaust port, or ports, such as the port 20 in the shell 4 of the power cylinder. When the upper face of the power piston arrives at this port 20, a quantity of the operating fluid that is propelling this piston, passes out through the 45 port and substantially reduces the pressure in the power cylinder above the piston 2, to atmospheric pressure. However, before this occurs I provide for a cooling effect on the piston 2 through the medium of this port 20, which is, 50 of course, open to atmosphere. For this purpose I provide the piston 2 with a waist 21 of reduced diameter. In other words, the piston 2 comprises an upper head and an auxiliary lower head 22, and the outer face of the lower head 22 is 55 formed with a scraper ring 23 in groove 23a, and the groove has a plurality of small ports 24, which extend down from the annular groove 23a, and communicate with the interior of the sleeve 9 above the return piston 12 of the plunger. The interior of this sleeve above the return 60 piston 12 communicates through a passage 25 with a cooling chamber 26 cored in the main head or upper head of the piston 2. This chamber communicates with the space around the piston's waist, through a port 26a. This enables the cooling air that enters the annular space surrounding the waist 21, to find its way up into the cored chamber 26.

65 By reason of the reduction of pressure in the 70 gas that is driving the piston 2 forwardly at the time the same passes the port 20, there will be a retarding effect tending to reduce the acceleration of the power piston 2. This effect is enhanced by reason of the fact that in the design 75 of the machine the effective area of the under

side of the return piston 8 is considerably greater than the effective area on the under side of the return piston 12 of the plunger. On this account the resistance to the advance of the power piston by the air in the cylinder 10, is considerably greater than the resistance to the advance of the return piston 12. In this way a separation between the power piston and the plunger is effected. One of the main advantages of this is that when the plunger delivers its blow, there is little or no shock from the blow imparted to the power piston, and this considerably increases the life of the packing rings 27 of the power piston 2.

It is necessary to provide for lubrication of the return piston 12 as it reciprocates within the sleeve 9 of the power piston 2. For this purpose I provide a lubrication connection 28 that admits a lubricant such as oil into the space surrounding the waist 21 and into the annular groove 23a whenever the power piston passes this lubricator and this oil is scraped down by the ring 23, and passes down through the ports 24 into the interior of the sleeve 9 above the return piston 12 of the plunger.

As many milled ores are subjected to cyaniding processes, and as the presence of oil in such a milled ore is objectionable, I prefer to construct this machine so that lubricating oil used in the machine cannot pass down into the vicinity of the die 7 where the ore is milled. In order to accomplish this, I prefer to provide the shoe 6 with a shell-form cap 29 secured rigidly to it, and this cap 29 is formed with a long upwardly extending outer sleeve 30, which reciprocates within an outer tubular casing 31, said casing 31 being preferably formed with an external flange 32 near its lower end for supporting the same above a mortar box 33, as will be described more in detail hereinafter. This sleeve 30 not only 40 prevents the passage of oil down to the shoe 6, but also affords means for operating the automatic mechanism of the machine when in operation, as will be described hereinafter. The machine is constructed so that it feeds ore onto the 45 die 7 automatically, and this automatic feed is controlled through the agency of the proximity of the shoe 6 to the die 7 after the blow has been struck on the ore lying on the die. In the present instance I utilize the sleeve 30 for controlling the ore-feeding device. The ore-feeding device 50 comprises a gate 34 preferably guided for vertical movement so that it can control flow of ore down a chute 35 into the mortar box 33. If the ore on the die 7 requires replenishing, the upper edge 30a of the sleeve 30 will pass below the inner end of a trip lever 36, which trip lever, with the roller on its forward end, will be projected forwardly by a coil spring 37 so that the roller at its forward end will be in the path of 55 the edge 30a when the plunger starts its upward movement. This trip lever 36 is preferably formed with a wide central slot as shown, which guides the lever so that it can slide on a fixed roller 38. The axial pin of this roller is mounted for adjustment in a vertical slot 39 in the frame of 60 the machine. When the inner end of the trip lever 36 is rocked upwardly, its upper side operates a rock lever 40 pivoted on a pin 41, and this lever engages a collar on a valve stem 42, thereby 65 opening the air valve 43 admitting air from an air chest 44 down a pipe connection 45, so that this air is admitted under the piston 46 moving in an air cylinder 47. This piston 46 fits loosely 70 in its cylinder and has a stem 48 extending down-

75

wardly, and attached to the gate 34. With this construction it will be evident that when the trip lever 36 is actuated, compressed air will be admitted under the piston 46, thereby raising the gate and admitting a quantity of ore through the chute 35. After the gate has been opened in this way, and the piston 46 rises above the outlet port 47a in the wall of cylinder 47, it will be returned to its closed position by a coil spring 49 associated with the stem 48.

The air chest 44 is connected by a suitable connection 50 with the air pipe 19 already described. An adjustable stop 51 for the trip lever 36 is provided, and this stop may be clamped in any desired position in a vertical slot 52 in the frame of the machine. The rocker lever 40 is held in contact with the trip lever 36 through the agency of a coil spring 53 disposed around the stem 54 guided through a small block 55.

The head 56 of the power cylinder 1 is provided with a main exhaust valve 57, the stem of which is guided through the head 56 so as to be actuated by a rock lever 58. This valve 57 is normally held closed by a coil spring 59. This valve 57 is opened automatically during the up-stroke of the plunger through the agency of the sleeve 30. For this purpose I provide a trip lever 60 that is pivotally attached near its middle point to the lower end of a slide bar 61, and the outer end of this lever is pivotally attached to a holding lever 62, which is pivoted at its upper end in an adjustable frame 63, the lower end of the lever 62 being provided with a small coil spring 64 that holds a roller on the forward end of the lever 60 against the side of the sleeve 30 while the plunger is elevated, and the spring 64 will, of course, force the roller on the forward end of the trip lever 60 into the path of the edge 30a of the sleeve 30 when the plunger is near the lower end of its down stroke. Hence on the upward movement of the plunger 3, the upper edge 30a of the sleeve 30 will trip the trip lever 60 in an upward direction. This will cause the slide bar 61 to move upwardly and open an air admission valve 65, which admits air from an air chest 66 to the under side of the piston 67, moving in a small air cylinder 68. The rod of this piston is extended to form an actuating stem 69 that thrusts against the long arm of the rock lever 58. In order to actuate the valve 65, the slide bar 61 carries a stem 70 with an adjustable collar 71 that engages the lower end of the stem of the valve 65. This valve 65 is normally held closed by a coil spring 65a; and, furthermore, the actuating stem 70 is returned by a small coil spring 70a. The actuating stem 69 for the rock lever 58 is also returned, together with the piston 68, by a coil spring 69a. In this way, soon after the plunger 3 commences its up-stroke, the exhaust valve 57 is open to atmosphere to permit exhaust of the operating fluid, or spent gases of combustion, in the power cylinder 1.

Means is provided for automatically closing this valve 57 near the termination of the up-stroke of the plunger and power piston 2. For this purpose I provide a trip lever 72 that is engaged by the upper edge 30a of the sleeve 30. Fig. 1 shows this edge 30a engaging this lever. This will cause the lever 72 to rock in an upward direction, and against a slide bar 73 that is pivotally attached to it, said slide bar operating to raise the valve stem 74 of an air exhaust valve 75 connected with the valve chest 66. The raising of this valve 75 permits the air under the piston 67 to exhaust to atmosphere through the

port 76. This valve 75 is normally held closed by a coil spring 74a around the stem 74.

The upper end of the slide bar 73 has a roller 77 rolling on the inner side of a guide bar 78, and the slide bar 73 is normally held up against the guide bar 78 by a coil spring 79. This coil spring also operates to pull the slide bar 73 and the lever 72 down to an extreme low position. In other words, the spring 79 will hold the inner end of the lever 72 against the outer face of the sleeve 30 when the upper edge 30a of the sleeve is located above this trip lever.

The exhausting of the compressed air from under the piston 68 of course, permits the exhaust valve 57 to be closed by its spring 59.

During all the time that the plunger 3 is below the position in which it is shown in the drawings, compressed air, or other operating fluid, is admitted to the interior of the return cylinder 10. This air, however, is not admitted through the pipe 19, but through another pipe connection 80, which admits air to a valve chest 81 in which a gate valve 82 slides. This gate valve is housed in a post 81a that passes up through the valve chest. In the position of the parts illustrated in the drawings, the upper end of the gate valve 82 is below two aligning ports 83 that permit air to flow across the upper face of the gate, and into an air passage 84, also housed in post 81a, and duct 85 in the upper end of the return cylinder 18, which duct 85 communicates with a tube 86 that extends down through air jacket space 18, and admits air into the lower end of the return cylinder 10 near the air head 14. However, on the up stroke when the edge 30a of the sleeve 30 engages a trip lever 87, it moves the valve 82 upwardly, and closes the ports 83. For this purpose the trip lever 87 carries a link 88, the upper end of which is pivotally attached to a slide block 89, said slide block being secured to the stem 90 of the gate valve 82. This gate valve 82 is normally held in a depressed position by a coil spring 90a disposed around the stem 90.

The supporting pin 81 for the trip lever 87, is preferably mounted for adjustment in a slot 92 in a portion of the frame of the machine.

The time of operation of this cut-off valve 82 determines the amount of power employed in the return of the plunger 3, and the power piston 2; and if more travel in return of these parts is required, the trip lever 87 should be adjusted so as to give a later cut-off for the valve 82. This trip lever 87 is preferably also utilized to control the admission of operating fluid, or combustible fuel, to the power cylinder 1, as will be described hereinafter.

The return piston 8 is preferably utilized to enable this machine to supply its own compressed air to keep it running after the machine has once been put into operation. For this purpose the upper end of the return cylinder 10 is surmounted by an air head 93 having an air inlet valve 94, which admits free air from the atmosphere on the down stroke of the return piston 8, and this air head is also provided with an outlet valve 95, which opens on the up stroke to permit compressed air in the upper end of the return cylinder 10 to pass out into the valve chest 81 already described; and this air, forced into valve chest 81 past the valve 95, passes up around the post 81a as indicated by the arrow in Fig. 1, and thence back into pipe 80 back to the air reservoir.

This air pipe 80 leads up to a fuel injecting device 96, preferably including a valve 98 which, when opened, admits the air under pressure into

an air admission duct 100 that leads through a poppet valve 101 into the interior of the power cylinder 1. The seat of the valve 99 has a countersunk fuel groove 111a with passages 111b leading onto the seat, and to which liquid fuel may be admitted from the fuel reservoir 102. When the valve 99 is open, air rushes through the inlet port 103 for this fuel, and carries a quantity of fuel with the air down through the duct 100 and past the valve 101 into the interior of the power cylinder. This valve 99 is opened automatically at the proper time through the agency of the rock lever 87, already described. For this purpose the rock lever 87 carries a stem 104, which stem shoves upwardly against a rock lever 105, said rock lever pivotally carrying an actuator 106, which is formed with a cam edge 107 cooperating with a roller 108 adjustably mounted in a slot 108a in a fixed bracket 108b. The actuator is held against the roller by a coil spring 106a. The upper end of the actuator 106 will thrust against the shoulder 109 and raise the rocker 110. However, the latter part of the movement of the actuator 106, and its cam edge 107, will cause it to swing outwardly at its upper end, thereby disengaging the shoulder 109 and permitting the rocker 110 to fall. The rocker 110 through an adjustable set screw, engages the stem 99a of the valve 99, which stem has a return spring 99b. The valve 99 is opened and the fuel admitted just before the termination of the up stroke. When the valve 99 is opened, by reason of the prior closing of ports 83, a quantity of air from the lower end of the return cylinder will flow up through tube 86 and follow up the air flowing into the power cylinder from air pipe 97. The removal of this air from under return piston 8 reduces the air pressure in the lower end of the return cylinder, and consequently reduces the resistance to the plunger 3 in its down stroke. The charge of fuel and compressed air admitted into the power cylinder 1, is ignited automatically, preferably by means of a spark plug 111, the circuit of which is closed at the proper instant, by means of a pivoted circuit closer 112, which is shoved upwardly at the proper instant by a small plunger 113 actuated by a link 114, the lower end of which is pivotally attached to the rocker 105. The rocker 105 is returned by a suitable coil spring 105a. The stem 99a of the valve 99 is preferably actuated from the rocker 110 through an adjustable set screw 110a.

When the circuit closer 112 engages the terminal 115, the circuit through the spark plug 111 and through a spark coil 116, will be closed, thereby producing an ignition spark in a recess in the wall of the power cylinder. This ignition, however, will take place after the admission of the fuel and air through the duct 100 has terminated, and the valve 101 has closed.

The air pipe 97 extends over to the right side of the machine as illustrated in Fig. 1, and is provided with a bent end 97a that is connected into the air chest 66 associated with the admission valve 65 that admits air under the piston 67 for operating the exhaust valve 57.

The machine is constructed so that the length of stroke of the shoe 6 can be adapted to the character of the ore being milled. If the ore is relatively hard, or difficult to mill, the plunger 3 should have the greatest possible stroke so as to increase the energy of the blow delivered to the ore on the die 7. On the other hand, if the milling operation is easy, the length of stroke

may be shortened. In order to enable this to be accomplished, all of the connections for the rocking parts controlled by the sleeve 30, should be adjustable. In order to regulate the stroke of the plunger, I prefer to employ a series of distance rings 117. These rings are preferably formed in sections, which may be put in place under the flange 32 of the casing 31. They operate to support the casing 31 at a more or less elevated point above the mortar box and the die 7. These distance rings may be of different thicknesses so as to give considerable range in the regulation of the stroke. They are held in place by clamping bolts 118 that pass down through the flanges and through the rings 118, and also through a base ring 119. The lower ends of these bolts are threaded into a "nut" ring 120 on the under side of the cover wall 121 of the mortar box.

The inner face of the wall of the lower part of the mortar box 33 is preferably protected by means of a liner 122 in which the die 7 is set. The milled material floats out through a screen 123 on one or more sides of the mortar box, said screen being clamped in place by a frame 124 and wedges 125 applied at the ends of the frame.

In order to assist in preventing any oil from passing down into the mortar box, and also so as to provide efficient guiding means for the plunger stem 3a that extends down from its return piston 12, I prefer to provide the air head 14 with an upwardly extending long tubular sleeve 126, which fits closely to the diameter of the stem 3a, which is preferably slightly enlarged at this point. The upper end of this enlarged neck of the stem 3a is preferably provided with suitable packing rings 127.

In order to enable the trip levers 36, 60, 72, and 87 to cooperate with the upper edge 30a of the sleeve 30, the wall of the outer casing 31 is provided with openings such as the opening 128, that pass through the same.

The shoe 6 is preferably connected to the lower end of the stem 3a in such a way that a certain amount of cushioning effect is obtained in imparting the thrust of the plunger to the shoe. For this purpose I prefer to form the lower end of the stem 3a with a substantially spherical ball head, or ball 129, and this ball is received in cooperating sockets formed between a lower block 130 and an upper block 131, the said upper block being provided with an over-size opening 132 through which the stem 3a passes downwardly.

These blocks fit down into a cylindrical chamber 133 in the upper side of the shoe. The blocks 130 and 131 are also cylindrical in horizontal cross-section, and are held in place in a steel shell, or sleeve 134, on the outer side of which a shell 135 of relatively soft packing material such as fiber, or similar material, is provided. The upper block 131 is held in position by means of the usual arcuate locking segments 136 that are dropped down through arcuate slots 137 on the upper side of the block, and then pushed circumferentially around in an arcuate chamber formed between two annular grooves, namely, a groove 131 formed in the inner face of the wall of the shoe at this point, and a cooperating groove 138 formed in the outer face of the upper block 131.

Between the lower face of the lower block 130 and the upper face of the body of the shoe 6, I provide a plurality of cushioning discs 139. These discs 139 give a slight amount of cushioning effect, and while they do not detract from

the blow given by the shoe 6 to the material on the die 7, they give a certain amount of "follow-up" to the blow, and they also relieve the upper mechanism of the machine of considerable shock.

I shall now describe briefly the mode of operation of the machine in passing through a complete cycle.

It should be understood that in the position illustrated in Fig. 1 for the power piston 2 and the plunger 3, these parts have traveled downwardly approximately an inch, or thereabouts, from the extreme upward limit of their travel. In other words, the explosion of the fuel has taken place, and the power piston 2 and plunger 3 are commencing their downward stroke. As this movement continues, a high amount of acceleration is imparted to these parts. As the waist 21 of the power piston 2 arrives opposite the port 20, atmospheric air is admitted around the waist 21, which tends to cool the power piston. As the movement continues, as soon as the upper face of the power piston 2 arrives at this port 20, an auxiliary exhaust of the propelling gases behind the piston 2, occurs. This reduces the impelling power on the power piston, and tends to check the advance of this piston with the plunger 3. Furthermore, by reason of the fact that the effective area of the under side of the return piston 8 is considerably greater than the effective area of the under side of the return piston 12 of the plunger 3, the air within the return cylinder 10 will offer greater resistance to the advance of the return piston 8, and this will assist in retarding it and effect a separation between the upper end of the stem 3a and the power piston 2, and hence when the blow is delivered to the material on the die 7, the power piston 2 will be out of contact with the plunger, and will not receive any shock from the sudden arrest of the plunger. Of course, the power piston will continue its forward movement, but its acceleration will have been retarded by the partial exhaust through the port 20, so that although the power piston 2 will follow up and strike the plunger, it will not be greatly jarred from striking it. Furthermore, a certain quantity of air from the annular space surrounding the waist 21 will find its way into the space between the power piston 2 and the end of the plunger 3, thereby giving an air cushion effect. When the blow is struck on the ore on the die 7, if it should happen that the ore on the die needs replenishing, then the plunger will have descended to such an extent that the upper edge 30a of the sleeve 30 of the plunger will have passed below the forward end of the trip lever 36. If this occurs, then when the plunger commences its return stroke, the edge 30a of the sleeve 30 will rock the trip lever 36 upwardly, thereby actuating the rock lever 40 and thereby raising the valve stem 42 to open the valve 43. This will admit compressed air from the pipe 19 and connection 50 to the pipe connection 45 that delivers air under the piston 46 in the cylinder 47. This will raise the piston, and the stem 49 of the piston will pull up the gate 34 and permit some ore to pass down the feed chute 35 into the mortar box. When the piston 46 passes the exhaust port 47a, the compressed air under the piston escapes and the spring 48 returns the gate 34. As this occurs the air in the cylinder escapes past the loose piston 46.

Referring again to the downward stroke of

the plunger 3 and power piston 2, it should be understood that compressed air is present in the return cylinder 10, and a quantity of this compressed air is forced out through the valves 13 in the air head. This air passes up through the ports 12 into the air jacket space 18 around the cylinder 10, and thence passes through the pipe 19 back to the air reservoir.

The plunger and the power piston commence to rise immediately after striking, by reason of the fact that compressed air will flow through the air supply pipe 80 and through the ports 83 of the valve chest 81, and thence through the passages 84 and 85 to communicate with the tube 86, which will deliver air at the lower end of the cylinder 10 and under the return piston 8. This air, of course, will commence to raise the power piston by reason of the force which it exerts upon the under side of the return piston 8; it will also commence to raise the plunger by reason of the force which it exerts on the under side of the return piston 12.

During the downward movement of the plunger, as it approaches the bottom of its travel, the upper edge 30a of the sleeve 30 will pass below the inner end of the trip lever 60, and hence the spring 64 will pull the trip lever 60 inwardly so that the roller on its forward end projects into the path of the edge 30a. Hence during the up-stroke, when the edge 30a strikes the lever 60, it will rock the lever on its pivotal support on the hanging lever 62, thereby exerting an upward thrust in the slide bar 61. This will cause the collar 71 to open the air admission valve 65, which will admit compressed air under the piston 67, raise the stem 69, and thereby rock the rock lever 58, which will open the exhaust valve 57. This reduces pressure of the gas of combustion above the power piston 2, and enables the piston as it rises, to completely exhaust the power cylinder 1. As the upward movement continues, the edge 30a eventually strikes the trip lever 72, which raises the slide bar 73, and this opens the air release valve 75, permitting the air under the piston 67 to exhaust. This permits the exhaust valve 57 to close preparatory to the power cylinder 1 receiving the explosive or combustible charge which is to be consumed for causing the next down stroke of the plunger.

Referring again to the down stroke of the plunger, it should be understood that as the return piston 8 moves downwardly in the return cylinder 10, the upper end of the return cylinder 10 operates as a compressor cylinder, atmospheric air being admitted through the inlet valve 94; and when the up-stroke commences, this air is forced out through the delivery valve 95, and passes through the air chest 81 and around post 81a as indicated by the arrow, and thence through pipe 80 back to the air tank, or reservoir. Just before the up stroke of the plunger and power piston is completed, the edge 30a of the sleeve 30 strikes the trip lever 87, the first effect of which is to actuate the link 88 that shoves the gate valve 82 upwardly and closes the ports 83. After these ports close, the fuel valve 99 opens and air flows into the power cylinder 1 from air pipe 97, followed up by air that flows out of the lower end of return cylinder 10. This air is for combustion of the fuel when ignited in the power cylinder 1 above the power piston 2. The movement of the trip lever 87, through the stem 104 housed in post 81a, actuates the rock lever 105, thereby moving the

actuator 106, the upper end of which engages on shoulder 109, causing the rock lever 110 to rise, thereby opening the air admission valve 99 and then permitting the same to close quickly by reason of the cam edge 107 on the actuator 106 that moves it back out of engagement with the shoulder 109. The opening of this valve 99, of course, permits the compressed air to flow in past the valve 99 into the air duct 100, thereby entraining liquid fuel from the fuel reservoir 102. This duct 100 also operates as a vaporizing chamber and mixer for the fuel and air; the air blowing into the duct or chamber 100, opens the valve 101, thereby bringing the explosive charge into the power cylinder 1. As soon as the valve 99 is permitted to close, of course, the valve 101 is immediately closed by its own spring. A continued upward movement of the rock lever 105 will push the plunger 113 far enough up to cause the circuit closure 12 to touch the terminal 115, thereby closing the circuit through the spark plug 111, and igniting the charge.

The stroke of the plunger is regulated with respect to the die 7, by changing the distance rings 117 and 118 under the flange 32 of the outer casing 31 of the machine. When the material being milled is soft, or easily milled, the stroke of the plunger should be reduced by removing the distance rings and permitting the flange 32 to rest on the base ring 119.

The feature in the mode of operation of this mill involving the withdrawal of air from the under side of the return piston 8 for admission into the power cylinder for burning the fuel therein, is highly advantageous because it substantially reduces the pressure of the air under the return piston 8, and under the return piston 12 of the plunger. This greatly reduces the resistance to the plunger on its down stroke, and enables a blow of a given amount of energy to be delivered with a relatively small quantity of fuel. In other words, this insures a considerable economy in the operation of the mill.

Ample energy is developed on the return stroke of the return piston 8 for lifting the same and the plunger 3. In this movement, if the return piston should lag, the plunger will overtake it, so that the effective area for lifting both these parts is the sum of the areas of the lower faces of pistons 12 and 8.

What I claim is:

1. In a machine for reciprocating a plunger, the combination of a floating plunger, means for guiding the same, a power cylinder, a power piston unattached to the plunger and located back of the plunger, means for developing pressure in the power cylinder to drive the power piston and the plunger forward, and means for returning the plunger.

2. In a machine for reciprocating a plunger, the combination of a floating plunger, means for guiding the same, a power cylinder, a power piston unattached to the plunger and located back of the plunger, an admission valve for the power cylinder, an exhaust valve for the power cylinder, and means controlled by the plunger for controlling the said valves.

3. In a machine for reciprocating a plunger, the combination of a floating plunger, guiding means for the same, a power cylinder adjacent the rear end of the plunger, a power piston in the power cylinder unattached to the plunger and mounted to reciprocate in the power cylinder, means for admitting combustible fuel and igniting the same in the power cylinder to drive for-

ward the power piston and the plunger, and pneumatic means for returning the plunger and the power piston.

4. In a machine for striking blows, the combination of a floating plunger, guiding means for the same, a power cylinder adjacent the rear end of the plunger, a power piston mounted to reciprocate in the power cylinder, means for developing gas pressure in the power cylinder to drive forward the power piston and the plunger, a return piston connected with the power piston, and means for admitting fluid to the return piston for returning the same.

5. In a machine for striking blows, the combination of a floating plunger, guiding means for the same, a combustion cylinder, a power piston mounted to reciprocate therein, means for feeding a combustible mixture into the combustion cylinder and for igniting the same to drive forward the power piston and the plunger, a sleeve carried by the power piston and sliding in the power cylinder, a return piston on the plunger within the sleeve, a return cylinder for the power piston, a return piston on said sleeve mounted to reciprocate in the said return cylinder, and means for admitting a fluid to said return pistons to return the same after the plunger has struck a blow.

6. In a machine for striking blows, the combination of a floating plunger, guiding means for the same, a combustion cylinder, a power piston mounted to reciprocate therein, means for feeding a combustible fuel into the combustion cylinder and for igniting the same to drive forward the power piston and the plunger, a sleeve carried by the power piston and sliding in the power cylinder, a return piston on the plunger within the sleeve, a return cylinder for the power piston, a return piston on said sleeve mounted to reciprocate in the said return cylinder, means for admitting a fluid to said return pistons to return the same after the plunger has struck a blow, and automatic means for effecting the exhaust of the spent gases of combustion controlled by the return movement of the plunger.

7. A machine constructed in accordance with claim 4, in which means is provided for permitting the exhaust of gas from the power cylinder before the blow is struck.

8. In a machine for striking blows, the combination of a floating plunger, guiding means for the same, a combustion cylinder, a power piston mounted to reciprocate therein, means for feeding a combustible mixture into the combustion cylinder and for igniting the same to drive forward the power piston and the plunger, a sleeve carried by the power piston and sliding in the power cylinder, a return piston on the plunger within the sleeve, a return cylinder for the power piston, a return piston on said sleeve mounted to reciprocate in the said return cylinder, means for admitting air in the return cylinder to exert pressure on the forward sides of the return pistons on the return stroke, and means for effecting a partial exhaust of the gas pressure from the power cylinder before the end of the forward stroke, and cooperating with the air pressure in the return cylinder to retard the power piston and separate the same from the plunger before the blow is struck.

9. In a machine for striking blows, the combination of a floating plunger, guiding means for the same, a combustion cylinder, a power piston mounted to reciprocate therein, means for feeding a combustible mixture into the combustion

cylinder and for igniting the same to drive forward the power piston and the plunger, a sleeve carried by the power piston and sliding in the power cylinder, a return piston on the plunger 5 within the sleeve, a return cylinder for the power piston, a return piston on said sleeve mounted to reciprocate in the said return cylinder, means for admitting air to the return cylinder to exert pressure on the forward sides of the return piston 10 tons on the return stroke, the area of the return piston of the power piston being greater than the area of the return piston of the plunger so that as the power piston and the plunger advance, the power piston will be retarded and out 15 of contact with the plunger when the blow is struck.

10. In a machine for striking blows, the combination of a floating plunger, guiding means for the same, a combustion cylinder, a power piston 20 mounted to reciprocate therein, means for feeding a combustible fuel into the combustion cylinder and for igniting the same to drive forward the power piston and the plunger, a sleeve carried by the power piston and sliding in the power 25 cylinder, a return piston on the plunger within the sleeve, a return cylinder for the power piston, a return piston on said sleeve mounted to reciprocate in the said return cylinder, means for admitting a fluid to said return pistons to re- 30 turn the same after the plunger has struck a blow, said plunger having a head at the forward end thereof, and said head having an outer sleeve extending therefrom and toward the power piston, and means actuated by the outer sleeve 35 for effecting the exhaust of the spent gases of combustion during the return movement of the plunger.

11. In a machine for striking blows, the combination of a floating plunger, guiding means for the same, a combustion cylinder, a power piston 40 mounted to reciprocate therein, means for feeding a combustible fuel into the combustion cylinder and for igniting the same to drive forward the power piston and the plunger, a sleeve carried by the power piston and sliding in the power 45 cylinder, a return piston on the plunger within the sleeve, a return cylinder for the power piston, a return piston on said sleeve mounted to reciprocate in the said return cylinder, means for admitting a fluid to said return pistons to return the same after the plunger has struck a blow, said plunger having a head at its 50 forward end and said head having an outer sleeve extending therefrom and toward the power piston, an exhaust valve for the power cylinder, 55 pneumatic means for opening the exhaust valve actuated by the said outer sleeve during the return movement of the plunger, and means also actuated by the outer sleeve in the return movement of the plunger for effecting the closing of the exhaust valve toward the end of the return movement of the plunger and the power piston.

12. In a vertical type machine for striking blows and capable of being used as a stamp mill, 60 the combination of a floating plunger, guiding means for guiding the same to reciprocate along a substantially vertical axis, a power cylinder coaxial with said plunger, a power piston mounted to reciprocate therein, means for feeding a combustible fuel into the power cylinder and for igniting the same to drive forward the power 65 piston and the plunger, a sleeve carried by the power piston and sliding in the power cylinder, a return piston on the plunger within the sleeve, a return cylinder for the power piston, a return

5 piston for the power piston mounted to reciprocate in the said return cylinder, means for admitting a lubricant to the interior of the power cylinder to lubricate the power piston and its sleeve, means for admitting an operating fluid 10 to said return pistons to return the same after the plunger has struck a blow, said plunger having an outer sleeve extending upwardly therefrom of larger diameter than the return piston of the sleeve, and operating to prevent passage of any 15 of the lubricant downwardly past the plunger head.

13. In a machine for striking blows, the combination of a floating plunger, guiding means for the same, a power cylinder, a power piston 15 mounted to reciprocate therein, means for feeding a combustible fuel into the power cylinder and for igniting the same to drive forward the power piston and the plunger, a sleeve carried 20 by the power piston and sliding in the power cylinder, a return piston on the plunger within the sleeve, a return cylinder for the power piston, a return piston on said sleeve mounted to reciprocate in the said return cylinder, means for 25 maintaining air in the return cylinder in advance of the return pistons, means for permitting exhaust of the said air as the return pistons advance in the forward stroke, an air admission valve for admitting air to the return cylinder 30 for returning the plunger and the power piston, and means controlled by the plunger in its return movement for closing said air admission valve.

14. In a machine for striking blows, the combination of a floating plunger, guiding means for the same, a power cylinder, a power piston mounted to reciprocate therein, means for feeding a combustible mixture to the power cylinder including an air duct, means for igniting the 40 mixture within the power cylinder to drive forward the power piston and the plunger, a sleeve carried by the power piston, a return cylinder with a compression chamber in its upper end, a return piston on the sleeve, sliding in the return 45 cylinder, means for admitting air to be compressed in the compression chamber when the power piston and plunger move forwardly, means for admitting air to the under side of the return piston to return the same and thereby return the 50 plunger, and deliver air from the compression chamber.

15. In a machine for striking blows, the combination of a floating plunger, guiding means for the same, a power cylinder adjacent the rear 55 end of the plunger, a power piston mounted to reciprocate in the power cylinder, means for developing gas pressure in the power cylinder to drive forward the power piston and the plunger, a return piston connected with the power piston, 60 and means for admitting fluid to the return piston for returning the same, said power cylinder having a port opening to atmosphere through the wall thereof adapted to be passed by the power piston in its forward stroke, and operating 65 to permit exhaust of gases of combustion from the power cylinder, said power piston having a reduced waist, said port also operating to admit air around the said reduced waist when the power piston is passing the said port, and thereby 70 cooling the power piston.

16. In a machine for striking blows, the combination of a floating plunger, guiding means for the same, a combustion cylinder, a power piston mounted to reciprocate therein, means for feed- 75

ing a combustible mixture into the combustion cylinder and for igniting the same to drive forward the power piston and the plunger, a sleeve carried by the power piston and sliding in the power cylinder, a return piston on the plunger within the sleeve, a return cylinder for the power piston, a return piston on said sleeve mounted to reciprocate in the said return cylinder, said return cylinder having an air head at the end thereof remote from the return pistons, valve means carried in the air head to permit air to be forced out of the return cylinder as the return pistons advance therein, said return cylinder having a jacket with means for circulating the air expelled through the said air head, and means for conducting the said air back to an air reservoir.

17. In a machine for striking blows, the combination of a floating plunger, guiding means for the same, a combustion cylinder, a power piston mounted to reciprocate therein, means for feeding a combustible mixture into the combustion cylinder and for igniting the same to drive forward the power piston and the plunger, a sleeve carried by the power piston and sliding in the power cylinder, a return piston on the plunger within the sleeve, a return cylinder for the power piston, a return piston on said sleeve mounted to reciprocate in the said return cylinder, said return cylinder having a head at its end remote from the return pistons, said head having a sleeve extending toward the power cylinder, and said plunger having a stem guided in the last-named sleeve.

18. In a machine for striking blows, the combination of a floating plunger, guiding means for the same, a power cylinder adjacent the rear end of the plunger, a power piston mounted to recip-

rocate in the power cylinder, a return cylinder, a return piston for the plunger cooperating with the return cylinder for returning the floating plunger after the same has delivered a blow, means for admitting compressed air under the return piston to return the floating plunger, valve means for admitting a combustible charge and air into the power cylinder at about the termination of the return stroke of the plunger, and means for effecting the delivery of a quantity of air from the under side of the return piston to the valve means for combustion in the power cylinder, thereby reducing the volume of air under the return piston on the down stroke, and reducing the air resistance to the plunger in its down stroke.

19. A machine constructed in accordance with claim 15, in which the power piston has a chambered upper head communicating with the air space around the waist of the power piston. 20

20. In a stamp mill, the combination of a floating plunger, guiding means for the same, an internal combustion power cylinder adjacent the rear end of the plunger, a power piston mounted to reciprocate in the power cylinder, means for compressing a charge and exploding the same in the power cylinder to drive forward the power piston and the plunger, a die cooperating with the forward end of the plunger to crush material, means for compressing air by the reciprocation of said power piston, with means for confining the same, and a pneumatically-controlled feeding device to receive a portion of said compressed air, for feeding material to the die, with means for controlling the admission of the compressed air to the same, brought into action by the proximity of the plunger to the die. 30 35

BENJAMIN B. BUCK.
